UNITED STATES PATENT OFFICE.

GEORGE A. BOYDEN, OF BALTIMORE, MARYLAND, ASSIGNOR TO THE BOYDEN BRAKE COMPANY OF BALTIMORE CITY, OF SAME PLACE.

PUMP-GOVERNOR.

SPECIFICATION forming part of Letters Patent No. 442,568, dated December 9, 1890.

Application filed July 25, 1890. Serial No. 359,938. (No model.)

To all whom it may concern:

Be it known that I, GEORGE A. BOYDEN, a citizen of the United States, residing at Baltimore, in the State of Maryland, have invented certain new and useful Improvements 5 in Pump-Governors, of which the following is a specification.

My invention relates to improvements in devices for controlling the flow and pressure 10 of fluids; and it consists of a governor that is particularly adapted to control the operation of the air-pump which provides the air-pressure for railroad-train brakes.

The construction of the device is such that 15 the use of diaphragms is avoided, and the air-pressure acting directly under a pop-valve will cause the supply of steam to be cut off, whereby the pump will be stopped when the air has reached the desired pressure and the 20 pump again started by the admission of steam thereto when the air-pressure has been lowered below a predetermined pressure. The governor may also be used for other like purposes.

25 The devices are hereinafter fully described, reference being had to the accompanying drawing, in which the figure shows a sectional view of the governor, the section being taken through the vertical axis thereof.

30 Similar numbers designate similar parts.

The number 8 denotes the body of the steam throttle-valve, which is in form similar to the globe-valves in common use, and in like manner is connected in the steam-pipe of the pump 35 by suitable unions in such way that the steam will flow therethrough in the direction indicated by the arrow. A wall 9, which divides the interior of this body into two chambers, having therein the opening 10, that is controlled 40 by the throttle-valve 11, which, when seated upon its seat 12, will close the communication between these two chambers and stop the flow of steam therethrough. This throttle-valve 11 is provided with the valve- 45 stem 13, that moves freely in the guide 14, that is secured to the body of the valve, and is provided with the packing-grooves 36 to prevent the escape of steam therethrough, the top of this valve-stem being rounded and 50 bearing on the under side of the piston 15,

which is free to move up or down in the cylinder 16, that is made integral with the valve-body 8, this piston 15 being of sufficient depth to form therein the packing-spaces 17, the spring 18 serving to normally hold the piston 55 up to the position shown in the drawing by one end thereof bearing on the under side of the piston and the other end resting on a suitable shoulder formed on the guide 14.

Bolted to the flange 19, with which the upper end of the cylinder 16 is provided, is the head 21, that forms a stop to the upward movement of the piston 15, and has therein the valve-chamber 20, that communicates through the port 22 with the air-pressure which is to 60 control the governor. The nipple 23 is made integral with the metal of the cylinder 16 and provided with a union by which the connection is made with a supply-pipe. To control the release of the air-pressure in the chamber 20, the pop-valve 24 forms a cover therefor, the knife-edge 26 of which seats upon the valve-seat 26, and its wings 27, moving freely in the chamber 20, serving as a guide therefor. In order to keep this pop-valve 24 on 65 its seat until the desired pressure is obtained thereunder through the port 22, the conical recess 37 is formed in the top thereof, in which rests the corresponding cone point 28 of the loose valve-stem 29, the upper end of this 70 valve-stem moving freely in the recess 30, formed in the adjusting-nut 31, the spring 32, placed under the adjusting-nut and pressing upon the collar 33 of the valve-stem, serving to hold the pop-valve 24 upon its seat 26 with 75 any desired pressure, which pressure may be varied by screwing up or down the adjusting-nut 31, which is threaded to the inner surface of the casing 34, that incloses this part of the governor. The cap 38 is threaded to 80 the adjusting-nut 31, by which the said nut is locked in position, a port 35 being provided in the head 21, whereby communication is established between the chamber formed by the casing 34 and that part of the cylinder 16 above 85 the piston 15, and whereby, when the pressure is sufficient to overcome the tension of the spring 32 and raise the pop-valve 24 from its seat, communication will be established 90 through the port 35 to the upper side of the 95 piston 15, and whereby, when the pressure is sufficient to overcome the tension of the spring 32 and raise the pop-valve 24 from its seat, communication will be established 100 through the port 35 to the upper side of the piston 15.

piston 15, which is of such area that the pressure thereon will overbalance the power exerted by the steam-pressure on the under side of the throttle-valve 11, the piston 15 will be moved downward, causing the throttle-valve 11 to be brought against its seat, and steam communication shut off and the pump stopped. It will thus be seen the pop-valve 24 is the controlling valve which governs the action of the throttle or steam valve 11. When the controlling-pressure in the chamber 20 has been reduced to a point which will permit the pop-valve 24 to be closed thereagainst by the tension of the spring 32, the pressure will be released from the upper side of the piston 15 by the escape of air past the sides of the piston, which is of a sufficiently loose fit for this purpose, and escape through the opening 40 in the side of the cylinder 16, which is formed therein below the piston 15, the pressure of the steam on the bottom of the throttle-valve 11 will cause the throttle-valve 11 to be raised from its seat, moving the piston upward to the position shown, and steam will be again admitted to the pump and the pump started to bring the air-pressure up to the required amount.

The port 22 is to be attached to a tank or device in which is held the pressure that is to control the governor.

I am aware that prior to my invention a diaphragm has been shown carrying a valve; but it has been found in practice that the

innumerable vibrations of the diaphragm cause radial formations or ribs therein, and this has the tendency to stiffen the diaphragm and render it uncertain in its action. I am also aware that piston-valves have been used; but they are objectionable, owing to the fact that they have to fit so neatly that a slight hardening of the oil or corrosion will cause them to stick. This difficulty is avoided in the present construction by the use of the pop-valve, which is free from connection or frictional contact with the walls of its chamber and must give under the pressure above and below, there being nothing outside the valve to prevent its action.

Having described my invention and the manner of operating, what I claim, and desire to secure by United States Letters Patent, is—

The described governor, consisting of a throttle-valve 11 and a piston 15 therefor, a supply-passage leading to said piston, and a pop-valve interrupting said passage, held in place by a spring, said pop-valve being free from connection with the walls of its chamber, substantially as described.

In testimony whereof I affix my signature in the presence of two witnesses.

GEORGE A. BOYDEN.
